CLAIM

The ornamental design for a bottle with diamond, as shown and described.

DESCRIPTION

FIG. 1 is a top perspective view of the bottle with diamond of my design with one diamond;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a top perspective view of a second embodiment of my new design;

FIG. 9 is a right side elevational view of the design of FIG. 8;

FIG. 10 is a left side elevational view of the design of FIG. 8;

FIG. 11 is a front elevational view of the design of FIG. 8;

FIG. 12 is a rear elevational view of the design of FIG. 8;

FIG. 13 is a top plan view of the design of FIG. 8; and,

FIG. 14 is a bottom plan view of the design of FIG. 8.

The broken lines in FIGS. 7 and 14 are included for the purpose of illustrating a portion of the bottom that forms no part of the claimed design.
